UNITED STATES PATENT OFFICE.

ARTHUR C. JACKSON AND FRANK SOLEY, OF PHILADELPHIA, PENNSYLVANIA,
ASSIGNORS TO MILLER LOCK CO., OF PHILADELPHIA, PENNSYLVANIA, A
CORPORATION OF PENNSYLVANIA.

POST-OFFICE BOX.

1,122,278.

Specification of Letters Patent. Patented Dec. 29, 1914.

Application filed April 19, 1913. Serial No. 762,200.

To all whom it may concern:

Be it known that we, ARTHUR C. JACKSON and FRANK SOLEY, citizens of the United States and residents of Philadelphia, county of Philadelphia, State of Pennsylvania, have invented certain Improvements in Post-Office Boxes, of which the following is a specification.

Our invention relates to certain improvements in that type of letter box known as the "nested" post office letter box in which there are a number of boxes or compartments arranged so that the mail can be inserted therein at one end and removed therefrom at the opposite end. In this type of box one end is entirely open to the mail distributing room, while the other end of the box is closed by a locked door or drawer.

Prior to our invention the usual practice has been to make the partitions of wood and to secure the front, carrying the door, to the wooden framework. In some instances, the partitions have been made of metal and a separate framework containing the doors was located in front of the partitions.

The object of our invention is to make a series of complete boxes, preferably entirely of metal, each box consisting of a bottom and two side plates, with a front plate and a door attached to the front plate and so arranged that a number of these boxes can be placed side by side one above the other so that, when assembled, they will form a comparatively rigid and substantial nested structure.

In the accompanying drawings: Figure 1 is a rear view of a nest of post office boxes illustrating our invention; Fig. 2 is a sectional view on the line *a*—*a*, Fig. 1; Fig. 3 is a sectional plan view on the line *b*—*b*, Fig. 1; Fig. 4 is a detached perspective view of one of the boxes looking from the rear; Fig. 5 is a detached perspective view of one of the boxes looking from the front with the door partly open; Fig. 6 is an enlarged longitudinal sectional view on the line *c*—*c*, Fig. 7, illustrating one box located on another; Fig. 7 is a sectional view on the line *d*—*d*, Fig. 6, showing two boxes arranged side by side and mounted on two other boxes; Fig. 8 is a sectional view on the line *e*—*e*, Fig. 7; Fig. 9 is a sectional view of a body on the line *d*—*d*, Fig. 6; Fig. 10 is

a perspective view of one of the front plates 55 with the door removed; Fig. 11 is a sectional view on the line *f*—*f*, Fig. 8; Fig. 12 is a sectional view on the line *g*—*g*, Fig. 8; Fig. 13 is an enlarged sectional view on the line *h*—*h*, Fig. 8; Fig. 14 is a detached perspective view showing the parts of the name plate; Fig. 15 is a perspective view of the U-shaped connection between the boxes; Fig. 16 is a sectional view on the line *i*—*i*, Fig. 8; Fig. 17 is a perspective view illustrating 65 a detail of the invention; Fig. 18 is a sectional view showing a modification in which the body forms a top and two sides of a box; Fig. 19 is a modification showing a body portion forming the top, bottom, and 70 two sides of a box; and Fig. 20 is a view of a box in which the frame is secured to the box before nesting.

Mail boxes in post offices are always arranged in nests and these nests vary in size, 75 as well as the individual boxes. The small boxes are usually provided with doors and the larger boxes instead of having doors are so made as to receive drawers, each drawer being locked to the front frame of the nest. 80 Boxes made in accordance with our invention are provided with doors or are arranged for the reception of drawers.

In Figs. 1 to 3 inclusive, we have illustrated a nest where there are five rows of 85 boxes. Six boxes in the top row; four in the next two rows; two in the next row beneath and two in the bottom row. This nest has a base and a top section and the boxes are held together by vertical and 90 transverse bolts. It will be understood that this is merely one nest and that the nests will vary according to circumstances.

Referring now to Figs. 4 and 5, 1 is the body portion of a box consisting of a plate 95 of sheet metal bent into shape, as illustrated in the drawings, and having a bottom 2 and sides 3—3. The sides have offset portions 4 which form the seat for the box in the tier above. Each box has flanges 5—5 at the 100 rear end which are turned out and back so as to fill the space at the back of a tier of boxes, as it will be understood that the side of one box is spaced from the side of an adjoining box so as to allow for the fastening 105 means, namely, the lugs on the front plates, the vertical bolts and the spacers and by providing the flanges at the back of each

box so that the space is filled, letters cannot be accidentally deposited in the space between the boxes.

When the boxes are assembled, the flanges extend upward between the boxes of the tier above, but when the boxes are arranged, as in the second tier, Fig. 1, then one flange of each box is cut away so that the side will abut the underside of the box in the upper tier.

Extending from the bottom of each box at the rear is a downwardly extending apron 6 and the apron of one box is spaced from that of an adjoining box, and these aprons can be bent to any angle desired after the nest of boxes is in place. A name plate 9 may be attached to the aprons and may extend from one side to the other of the nest of boxes. Each name plate may have a series of name card holders thereon, or the name may be painted directly on the plate, if so desired. In order to secure these name plates to the aprons of the boxes, we provide extended wide nuts 10 which underlap two adjoining aprons, as illustrated in Fig. 16. A screw 11 extends through the name plate and into this nut, rigidly confining the name plate to the aprons.

12 is the frame at the front of the box having rearwardly extending lugs 13 at each side. The lugs have countersunk openings for the reception of the rivets 14. The object of making these openings countersunk is to insure the head of the rivets from being flush with the inner face of the box when the rivets are headed, as in Fig. 11. The heads force the sheet metal of the box into the countersunk openings and the outer surface of each head of the rivet is flush with the surface of the plate forming the side of the box.

Projecting from the lower edge of each frame are lugs 15 which rest in recesses 16 on the upper edges of the box below it and also have rearwardly extending lugs 25 upon which rest the bottom 2 of the sheet metal body of the box. Thus, when the several boxes are assembled, the front plates 50 interlock so as to rigidly hold the parts together and to give a neat appearance to the front of a nest of boxes.

Pivotaly mounted on the frame, in the present instance, are doors 17, which are glazed in the ordinary manner and have the usual locks so that when these doors are opened, the letters, or other mail matter, can be removed from the boxes. In some instances, as mentioned above, and especially 60 in the larger boxes, drawers may be substituted for the doors without departing from the essential features of the invention, as the frames can be used with drawers, as well as with doors.

65 In order to hold the rear ends of the

boxes together, we press out from the side walls of each box near the upper end and, in the present instance, near the rear of the box, bands or blisters 18 for the reception of the arms of U-shaped spacers illustrated in Fig. 15. Transverse bolts 19 extend from one side of a nest of boxes to the other, holding them rigidly in position. These bolts pass through openings in the spacers as clearly illustrated in Figs. 8 and 13, locking the spacers rigidly in position. The transverse bolts also support the bottom of each box at the rear end. The upper portions of each U-shaped spacer 20 extends between the boxes of the tier above, as clearly illustrated in Fig. 7. Thus the boxes are held by the U-shaped spacers at the rear of the nest and by the arms at the forward end.

21 is the base of the end of each nest and 22 is the cap plate which is shaped so that the boxes are properly held. Vertical bolts 23 extend through the spaces between the boxes, preferably directly back of the U-shaped spacers and directly back of the lugs on the front plates and when these bolts are secured, the nest of boxes is held vertically, as well as transversely. Side plates may be located on each side of the boxes and held thereto by the transverse bolts and by flanges on the top plate and base, if desired. This will depend considerably upon the finish desired.

By the above construction it will be seen that we are enabled to make a nest of boxes entirely of metal, each box being complete in itself so that any number of boxes of any shape can be nested together to form a post office box structure. If alterations are desired, the nest of boxes can be dismantled and the boxes arranged as necessity demands.

In some instances, as shown in Fig. 8, the body portion of the box may be made in such a manner that the plate will form the top of the box and the two sides instead of the bottom of the box and the two sides without departing from the essential features of the invention.

Instead of making the body portion three-sided, as illustrated in the drawings, Figs. 4 and 5, they be made as illustrated in Fig. 19, in which each box has a top and bottom and two sides, made from a single sheet of metal, either bent and joined at the top or made from a seamless tube. In this construction the transverse bolt will pass between the bottom of one box and the top of another, as shown.

As above described, the body portion of the box is made independently of the front frame and both can be carried in stock in different sizes, so that an order can be filled by taking certain sizes of bodies and front frames to make up the nest. Prior to our invention this was impossible.

5 In some instances, each front plate may be firmly secured to its body portion by rivets or other fastenings, as in Fig. 20 and a U-shaped spacer or coupling 26 may be located at the front of the nest of boxes as well as at the rear, or one frame may be secured to its body by rivets, or other fastening means and through rivets may couple two boxes together side by side.

10 We have shown the boxes with solid bottoms, but the bottoms may be perforated in any manner desired.

15 While we have illustrated our invention as applied to post office boxes, it will be readily understood that it can be applied to filing cabinets, card index cabinets, or other containers, and that the forward frames can be slightly modified or omitted, and that drawers or the ordinary sliding file boxes may be 20 used in connection with the containers.

We claim:

1. The combination of a nest of post office boxes, each consisting of a single box having a body portion and front frame, one front 25 frame interlocking with another; means for keeping the boxes in alignment; and means for retaining the boxes in a nest.

2. The combination in a post office box of the type in which several boxes are nested 30 together to form a post office structure, each box consisting of a body portion formed of a single horizontal section and two sides, the other horizontal section being formed by an adjoining box so as to complete the closure; 35 and an individual front frame secured to the sides of said body portion.

3. The combination of a series of boxes, each having a body portion formed of a single horizontal section and two sides; each box 40 having a front frame secured thereto, the boxes being so arranged as to be placed side by side or one above the other; and means for securing a series of boxes together independently of the front frames.

45 4. The combination in a post office box, of a metallic body portion forming the floor and two sides of a box and an individual front frame secured to the body portion and having a supporting lip extending under the floor of the body portion.

50 5. The combination of two post office boxes arranged side by side, each box having a body portion forming a floor and two sides; a frame secured to the front of each box and an integral downwardly projecting apron extending from the rear of each box; and means for securing the aprons of adjoining boxes together.

55 6. The combination in a post office box, of a body portion; a front frame having rearwardly extending perforated lugs, the lugs of one plate alining with those of the plate of an adjoining box; and rivets passing through the lugs and securing the two boxes together.

7. The combination in a post office box, of a body portion made of sheet metal and having side plates; a front frame having rearwardly projecting lugs at each side arranged to extend outside of the side plates, the lugs having countersunk openings; the countersink being next to the side plate; the openings in one set of lugs alining with those on the plate of an adjoining box; and a rivet passing through both sets of lugs, the heads of the rivet and the inturned metal of the body resting in the countersink, the head of the rivet being flush with the plate.

8. The combination in a post office box, of a body portion made of sheet metal and forming the bottom and two sides, the upper ends of one side being offset to form a shoulder for the box directly above it; a front frame secured to the body portion and spacing members located between adjoining boxes 85 on the same plane; and transverse bolts securing the boxes together.

9. The combination in a post office box, of two metallic body portions; a blister bent from the side of each body portion; and a 90 U-shaped spacing member having arms, one arm extending through the blister of one box, the other arm extending through the blister of an adjoining box, said U-shaped member acting not only as a spacing means, 95 but also as a means for retaining the boxes in position.

10. The combination of a series of boxes, each box having a body portion; a frame secured to the front of each box, the side members of each box being cut and bent to form blisters; perforated U-shaped spacing members extending between the boxes and through the blisters; and transverse bolts extending through a series of the boxes and 105 through the perforations in the spacing members.

11. The combination of a series of boxes, each box having a body portion and a front frame; the body portion having out turned 110 flanges at the rear; and spacing members securing two boxes together on the same plane with the said flanges abutting.

12. The combination of a series of boxes arranged side by side; each box having a depending apron; a name plate extending in front of the aprons; nuts underlapping the aprons; and bolts extending through the name plate and engaging the nuts, whereby the plate is secured to the aprons. 115

13. The combination of a series of boxes arranged in a nest; vertical and transverse bolts securing the boxes together, each box having a sheet metal body portion and an individual front frame; said front frame interlocking; and means for securing the boxes together at the rear independently of the bolts.

14. The combination of a series of boxes arranged in a nest, each box consisting of a

4
body portion and a front frame, the front frame of each box being wider than the body portion; spacing members attached to the body portion of adjoining boxes of one tier and extending between the body portions of the boxes of another tier.

15. The combination of a series of containers arranged side by side and one above another; connecting members extending between two of said containers and engaging both of them and also extending between two containers of another set and forming a spacing means for said last mentioned containers.

16. The combination of two containers arranged side by side; bands on the adjoining walls of the said containers; and an attaching device having two arms arranged to enter the space back of the bands and to lock the two containers together.

20
In testimony whereof, we have signed our names to this specification, in the presence of two subscribing witnesses.
